UNITED STATES PATENT OFFICE.

IRA O. WEAR, OF OBERLIN, KANSAS.

SLEEPING DOLL.

No. 912,637.

Specification of Letters Patent.

Patented Feb. 16, 1909.

Application filed June 2, 1908. Serial No. 436,275.

To all whom it may concern:

Be it known that I, IRA O. WEAR, citizen of the United States, residing at Oberlin, in the county of Decatur and State of Kansas, have invented certain new and useful Improvements in Sleeping Dolls, of which the following is a specification.

The purpose of the present invention is to provide a doll or toy with an eye mechanism 10 of such construction and arrangement as to prevent displacement of the eyes after they have once been set, thereby overcoming the objectionable features incident to such toys as usually made, and at the same time producing the sleeping effects desirable in toys 15 having movable eyes.

The invention consists of fixed eyes, movable lids, a detent mechanism for securing the lids in a given position, preferably when 20 open, and which may be released by a jar, and peculiar mountings for the parts, all of which will appear more fully hereinafter.

The invention further consists of the novel features and details of construction which 25 hereinafter will be set forth, illustrated and claimed.

Referring to the drawings forming a part 30 of the specification: Figure 1 is a vertical central section through a doll's head, showing my device as applied. Fig. 2 is a plan view of the eye mechanism, showing it detached from the doll's head, the lids being open. Fig. 3 is a front elevation of the eye 35 mechanism, the lids being open. Fig. 4 is a detail perspective view of the lids and weight. Fig. 5 is a detail perspective view of the eye support.

Corresponding and like parts are referred 40 to in the following description and indicated in all the views of the drawings by the same reference characters.

The numeral 1 represents the head of the doll or other figure provided with the eye mechanism, said head having eye openings 45 2 through which the eyes 3 are seen. A bridge 4 is arranged within the head and supports the eyes 3 and may be of any construction. The eyes 3 may be secured to the bridge, or support 4, in any suitable manner. 50 It is proposed to mount the bridge, or support 4, in such a way as to admit of a limited movement, whereby the eyes 3 may fit close to the eye openings. The bridge, or support 4, in its preferred construction, consists of a 55 bar or strip having its end portions bent and secured to opposite sides of the head. Arms

5 project upwardly and rearwardly from the bridge, or support 4, and are connected at their upper rear ends by means of a cross-piece 6, which forms a stop to limit the 60 movement of a detent 7 which is mounted upon a pin 8 supported at its ends in the arms 5.

The lids 9 are connected by a yoke 10 which is pivotally mounted on the bridge, or support 4. A cross-piece 11 connects the inner ends of the lids 9 and is provided with a sleeve 12 which receives a staple 13, attached to the bridge, or support 4, and by means of which the yoke 10 and cross-piece 70 11 are pivotally connected to said bridge. A rod 14 extends downward and outward from yoke 10, and is provided at its lower end with a weight 15. A strip 16 is connected to the upper portion of the rod 14 75 and provides an extended surface for the end of the detent 7 to ride upon.

The parts are so arranged that when the head 1 is in an upright position the weight 15 hangs pendent and holds the lids 9 in 80 approximately horizontal position so as to expose the eyes 3 through the eye openings 2.

When the lids are open the detent 7 engages over the yoke 10 and fixes the position of the lids and prevents their closing 85 except when the head is in horizontal position and the detent released from the yoke, thereby permitting the weight 15 to swing toward the back of the head and move the yoke so as to cause the lids to cover the 90 eyes 3. The stop portion of the detent is rounded or of such construction as to be readily disengaged from the yoke by giving the head a slight tap or jar after the doll or figure has been placed in a horizontal 95 position.

It will be readily understood from the foregoing description, taken in connection with the accompanying drawings, that the invention results in an eye mechanism for 100 dolls and like toys which will prevent the displacement of the eyes and insure handling of the toy without producing unnecessary movement of the eye mechanism in the head, and secures the same in place to permit the 105 eye mechanism as a whole to be easily, quickly and cheaply constructed and placed in position.

Having thus described the invention, what is claimed as new is:

1. In an eye mechanism for dolls and the like, the combination of movable lids, a

weight therefor, and a detent for holding the lids open.

2. In an eye mechanism for dolls and the like, the combination of a support provided with eyes, lids, a yoke connecting the lids and pivotally mounted upon said support, a weight having connection with the yoke for controlling the movement of the lids, and a detent pivotally supported by the said support and adapted to engage with the yoke and hold the lids open.

3. In an eye mechanism for dolls and the like, the combination of a bridge forming a support for the eyes, lids, a yoke connecting the lids, a cross-piece also connecting said lids, a pivotal connection between said cross-piece and bridge, a weight having connection with the yoke for controlling the move-

ment thereof and the lids, and a detent for holding the lids open and adapted to be released by means of a jar.

4. In an eye mechanism for dolls and the like, the combination of a bridge provided with eyes and having arms projecting therefrom, lids for covering the eyes, a yoke connecting the lids and pivotally mounted upon the bridge, a weight having connection with said yoke, and a detent pivoted to the said arms and adapted to hold the lids open, and adapted to be released by means of a jar.

In testimony whereof I affix my signature in presence of two witnesses.

IRA O. WEAR. [L. S.]
